UNITED STATES PATENT OFFICE

136,164

DESIGN FOR A BANDANNA

Arthur C. Radebaugh, Arlington, Va.

Application June 2, 1943, Serial No. 110,341

Term of patent 3½ years

To all whom it may concern:

Be it known that I, Arthur C. Radebaugh, a citizen of the United States, residing at Arlington, in the county of Arlington and State of Virginia, have invented a new, original, and ornamental Design for a Bandanna, of which the following is a specification, reference being had to the accompanying drawing, forming a part thereof.

The invention described herein may be manufactured and used by or for the Government for governmental purposes, without the payment to me of any royalty thereon.

The figure is a plan view of a bandanna showing my new design.

I claim:

The ornamental design for a bandanna, as shown.

ARTHUR C. RADEBAUGH.
